EXPANDING WEDGE

William Hejduk, Bronx, and Frank Ruoff,
Yonkers, N. Y.

Application May 29, 1940, Serial No. 337,928

5 Claims. (Cl. 254—104)

This invention relates to an expanding wedge particularly adapted to the breaking of contact shoes of subway or electric railway cars, and it consists in the construction, arrangement and combinations herein described and claimed.

It is an object of the invention to provide an expanding wedge of compact and sturdy construction which may be quickly applied to a contact shoe for the purpose of breaking the same.

It is also an object of the invention to provide a wedge in which a rigid jaw and a laterally movable jaw are interconnected in a removable manner, permitting replacement of either when and if found necessary.

It is a still further object of the invention to provide an expanding tool in which a sliding wedge is interposed between a rigid jaw and a laterally movable jaw, the wedges being so shaped as to exert an angularly directed pressure against the laterally movable jaw, thereby causing a quick breaking of the contact shoe.

Additional objects, advantages and features of invention will be apparent from the following description considered in conjunction with the accompanying drawing, wherein:

Figure 1 is a side elevation of the wedge installed upon a contact shoe, the latter being fragmentarily illustrated and in section.

Figure 2 is a front elevation of the wedge.

Figure 3 is a cross section on the line 3—3 of Figure 1.

There is illustrated in Figures 1 and 2, an expanding wedge, generally indicated by the reference character 10 and comprises a main jaw 11, of flat, elongated form. The upper portion of the jaw has integrally formed therewith a head 12 extended at right angles to the jaw, the latter having substantial thickness and provided with a threaded bore 13. The bore 13 extends in a plane parallel to the jaw and receives a threaded drive bolt 14 therethrough. The bolt 14 has its upper end shaped for reception of a ratchet wrench 15, generally indicated in Figure 1. The lower end of the bolt 14 has a reduced end 16 in which there is formed a circumscripting groove 17. The end 16 is revolvably seated within a bore 18 of a wedge member 19 the wedge being secured thereto by means of a drift pin 20 engaged in the groove 17, as clearly shown in Figure 3. By this construction it will be apparent that the drive bolt 14 may be readily rotated to impart outward or inward movement of the wedge 19.

A jaw 21 is provided arranged in parallel rela-

tion to the jaw 11, detachably connected to the head 12 and to this end, the head is formed with a pair of tapped bores 22 aligned with respective openings formed in the right angular flange 23 of the jaw. Machine bolts 24 engaged in the bores 22 will rigidly secure the jaw to the head.

Contact breaker shoes as employed upon subway and electric trains are constructed of cast iron and for the purpose of quickly removing the shoe from the train or car, the shoe is provided with an opening for insertion of a means for breaking the shoe. A portion of a shoe is indicated at 25 and the opening at 26.

The jaw 11 has its inner face 28 inwardly tapered in the direction of the vertical axis of the tool, and the outer face 29 is upwardly and outwardly tapered, the taper beginning at the seat 27.

The jaw 21 is formed from a piece of strap steel, the free end 30 of which is inclined inwardly toward the vertical axis of the tool.

The jaws 11 and 21 have complementary flat faces 31 spaced apart for reception of the wedge 19, as will be now described.

The wedge 19 has opposed tapering faces 32 and 33, terminating in a chisel-like edge 34 of a thickness so as to freely pass between the flat faces 31 of the jaws, but it should be noted that the taper of the face 33 is substantially parallel to the cooperating flat face 31 for a short distance and thence inclined outwardly, forming a depressed portion 35. Thus the inclined face above the portion 35 cooperates with the adjacent face 31 to exert an angular pressure upon the jaw 21 upon downward movement of the wedge, thereby quickly breaking the contact shoe.

The operation of the tool will be readily understood from the following description. The wedge 19 is drawn inwardly as in Figure 1, with the jaws 11 and 21 in normal position, permitting the jaws to be inserted in the opening 26 of the shoe, the seats 27 being aligned with the edges 45 of the opening. The bolt 14 is now rotated so as to move the wedge downwardly between the flat faces 31 until the depression 35 of the wedge engages the adjacent face 31. Continued rotation of the bolt will move the wedge still further causing outward flexing of the jaw 21, and since the line of travel of the face 33 and depressed portion 35 is angularly changed, a quick snapping action of the metal of the shoe will occur.

While we have shown and specifically described a preferred construction, this is by way

of illustration only, and we consider as our own all such modifications in structure as fairly fall within the scope of the appended claims.

We claim:

1. In an expanding wedge, a pair of jaws constructed for insertion and retention within an opening, a wedge member between the jaws and movable longitudinally thereof, said wedge having inwardly tapering side faces, and one of said side faces having a depressed portion therein to cause an angular movement of one of the jaws when said wedge is moved beyond the depressed portion.

2. In an expanding wedge, a rigid jaw and a resilient jaw connected thereto, said jaws being constructed for insertion and retention within an opening, a wedge member positioned between the jaws and of a length to be moved longitudinally between and beyond the extremities of the jaws, means for moving the wedge, and said wedge having upwardly tapering side faces, one of said faces having a depressed portion therein to cause an angular movement of the resilient jaw when said wedge is moved beyond the depressed portion.

3. In an expanding wedge, a rigid jaw having a right angular head, a resilient jaw mounted on the head, said jaws being constructed for insertion within an opening and having seats for engaging the side walls of an opening, a drive bolt threadedly engaged through the head and positioned between the jaws, a wedge member operatively connected to the bolt and positioned

between the jaws, said wedge being of a length to be moved longitudinally beyond the extremities of the jaws and the wedge having upwardly tapering side faces adapted to contact the jaws adjacent their extremities on downward movement of the wedge.

4. In an expanding wedge, a rigid jaw having a right angular head, a resilient jaw mounted on the head, said jaws being constructed for insertion within an opening and having seats for engaging the side walls of an opening, a drive bolt threadedly engaged through the head and positioned between the jaws, a wedge member operatively connected to the bolt and positioned between the jaws, said wedge being of a length to be moved longitudinally beyond the extremities of the jaws and the wedge having upwardly tapering side faces adapted to contact the jaws on downward movement of the wedge, one of said faces having a depressed portion therein to cause an angular flexing movement of the resilient jaw when said wedge is moved beyond the depressed portion.

5. In an expanding wedge, a pair of jaws constructed for insertion and retention within an opening, a wedge member between the jaws and movable longitudinally thereof beyond the extremity of the jaws, and said wedge having inwardly tapering side faces cooperative with the jaws for expanding the jaws when extended therebetween and beyond.
